[57] CLAIM

The ornamental design for a holder for paint application pad, substantially as shown and described.

DESCRIPTION

FIG. 1 is a top front perspective view of a holder for paint application pad, showing our new design; FIG. 2 is a top plan view thereof shown on a larger scale;

FIG. 3 is a bottom plan view thereof;

FIG. 4 is a front elevational view thereof;

FIG. 5 is a rear elevational view thereof;

FIG. 6 is a left side elevational view thereof.

FIG. 6
